UNITED STATES PATENT OFFICE.

JOHN JOHNSTON, OF LONDON, ENGLAND, ASSIGNOR TO ARCHIBALD EDWARD DOBBS, OF LONDON, ENGLAND.

FEED-WATER, BURNER, OR LIKE REGULATOR.

SPECIFICATION forming part of Letters Patent No. 704,842, dated July 8, 1902.

Application filed February 26, 1902. Serial No. 95,732. (No model.)

To all whom it may concern:

Be it known that I, JOHN JOHNSTON, a subject of the King of Great Britain and Ireland, residing at 19 Park road, New Cross, London, S. E., England, have invented a certain new and useful Improved Feed-Water, Burner, or Like Regulator, (for which I have made application for Letters Patent in Great Britain, No. 18,841, and dated the 20th day of September, 1901,) of which the following is a specification.

This invention relates to apparatus for regulating both the feed-water supply to boilers and the heating arrangements thereof.

The invention more particularly relates to boilers heated by oil and like burners as used upon motor-cars; but it is also applicable to other purposes.

The invention consists in interposing between the boiler and the feed-pump a regulator through which the feed-water has to pass on its way to the boiler, the said regulator being adapted, according to the boiler-pressure, to automatically control the amount of feed-supply and at the same time the burner or draft, according to which type of boiler it is applied.

In carrying the invention into effect in one convenient manner, as illustrated in the accompanying drawing, the regulator is constructed in the form of a cylinder *a*, fitted with a piston *b*, the rod *c* of which passes out at the top of the cylinder through a cylindrical extension *d*, having an internal diameter considerably larger than the piston-rod *c* and terminating in a stuffing-box of the usual form. This extension is in communication with the boiler-feed pipe *e* by a suitable passage *f*, controlled by a non-return valve *g* of the ball or other type. It is also in communication with the cylinder above the piston by means of a hole *h* in the cylinder-cover, through which the piston-rod passes. This hole *h* is of such diameter and the piston-rod *c* of such form that when the piston is in its lower or normal position there is sufficient area to allow full supply of feed-water to pass from the cylinder *a* to the boiler-feed pipe *e*; but when the piston rises the area is lessened

until at the highest position of the piston the hole *h* is completely filled up or closed by the

piston-rod and the boiler-feed thereby cut off. In order to accomplish this, the rod *c* is in one convenient form, as shown, tapered or enlarged at its lower part. The feed-supply from the pump is led to the upper side of the piston *b*, an air vessel *i* being interposed between the pump-supply pipe *j* and the cylinder *a*. A pipe *k* is led from this air vessel from a point at rather a high level in the same to a passage *l* in communication with a relief-valve *m*. The under side of the piston *b* is in connection by a passage *n* and suitable pipe *o* with the boiler-feed pipe *e* or with the steam-space, accordingly as the application is made to a flash or ordinary boiler, respectively. A safety-valve *p* is provided in connection with the under side of the piston and is preferably arranged in juxtaposition with the relief-valve *m*, before referred to, in order that both valves *m* and *p* may be loaded by the same spring *q*, which is caused to act upon a cross-lever *r* or bar bearing on both valve-stems, the spring, however, being adapted to bear nearer the safety-valve *p* than the relief-valve *m*, the former being thereby heavier loaded.

In operation the feed-pump is arranged to work continuously and also to pump a surplus of water, which escapes by way of the relief-valve *m*, a small shifting valve being provided, preferably, upon the feed-pump suction-pipe to enable a small quantity of air to be fed with the water in order to replenish the air vessel *i*.

It will be understood from the foregoing that the piston *b* is under boiler-pressure on its under side and feed-pump pressure on its upper side. Therefore when the boiler-pressure is low or normal the piston will be low and feed-water allowed to pass to the boiler; but when the boiler-pressure rises the piston ascends and cuts off the feed-supply to the boiler, the action being automatic.

In order to effect a regulation of the burner when oil is used or the draft when solid fuel is used corresponding to the variation of the boiler-pressure, the piston-rod *c* is extended and connected by a suitable joint *s* to one end of a rocking lever *t*, the other end of which is connected by a rod *u* with the burner or with the draft-regulator, as convenient. In order

to limit the movement of this rod *u* within the extreme range of the burner or draft-regulator, suitable stops *v* are provided, and a further adjustment is obtained by making the 5 fulcrum *w* of the rocking lever *t* movable. The fulcrum *w* in one form consists of a pin fixed to a nut traveled in guides *x* by a screw and hand-wheel *z*.

The invention is not confined to the exact details of construction hereinbefore described, as the same may be varied to suit the circumstances under which the improvements are to be applied.

Having thus described my invention, what 15 I claim as new, and desire to secure by Letters Patent, is—

1. An apparatus for simultaneously regulating the feed-water supply and heating arrangements for steam-boilers in accordance 20 with the variations in boiler-pressure consisting of, a cylinder divided by a piston into two chambers, one in constant communication with the boiler and the other interpolated between the feed-supply and the boiler, and a 25 conical or like piston-rod for controlling the feed-outlet from the latter chamber and connected to the burner-supply or furnace-draft regulating arrangements, substantially as hereinbefore described.
2. An apparatus for simultaneously regulating the feed-water supply and heating arrangements for steam-boilers in accordance 30 with the variations in boiler-pressure consisting of, a cylinder, a piston therein, an opening 35 in the cylinder-cover connecting one side

of the piston with a passage leading to the boiler and fitted with a non-return valve, a second passage leading from the feed-supply to the same side of the piston and fitted with an air vessel and relief-valve, a passage leading from the boiler to the other side of the piston and fitted with a safety-valve, a conical piston-rod, passing through the aforesaid opening in the cylinder-cover and connected to a rocking lever, a fulcrum for said lever 45 and screw adjustment therefor, and a rod provided with stops and connecting said rocking lever with the burner-supply or furnace-draft regulator, substantially as hereinbefore described. 50

3. In an apparatus for simultaneously regulating the feed-water supply and heating arrangements for steam-boilers in accordance with the boiler-pressure, comprising a cylinder fitted with a piston acted upon on one 55 side by boiler-pressure and on the other by feed-pump pressure the piston-rod controlling both the feed-supply and heating arrangements, the combination of a safety-valve and a relief-valve one connected to the 60 boiler side of the piston and the other to the feed side and both adjusted by the same lever and spring substantially as hereinbefore described.

In witness whereof I have hereunto set my 65 hand in presence of two witnesses.

JOHN JOHNSTON.
